REEL

Arthur Alfred Bureau, Chicago, Ill., assignor to
 Western Electric Company, Incorporated, New
 York, N. Y., a corporation of New York

Application October 11, 1927, Serial No. 225,456

4 Claims. (Cl. 206—59)

This invention relates to reels, and more especially to metallic reels for holding cable or other heavy material susceptible of being wound on reels.

5 Heretofore it has been the practice in many instances to construct the heads of reels for storing cables of wood in order that protecting lags might be nailed thereto. However, with the development of devices for retaining the lags on 10 the heads without nailing, it becomes advantageous to use reels provided with metallic heads.

The object of the present invention is to provide a strong and durable metallic reel of a simple and efficient design adapted to be provided with 15 enclosing elements.

In accordance with the general features of the invention a reel is provided consisting essentially of a flanged drum provided with heads having circumferential outwardly extending flanges for 20 accommodating wooden lags used to enclose the cable, and of means coacting with the head at the periphery and the outer edge of the circumferential flange to stiffen the former and support the latter.

25 The assemblage of the novel structure will now be described as disclosed in the accompanying drawing, like numerals being used for similar parts.

Fig. 1 is an end view of the assembled drum; 30 Fig. 2 is an enlarged sectional view of the reel taken on line 2—2 of Fig. 1 exposing a cable wound thereon;

Fig. 3 is a fragmentary enlarged cross-sectional view of a bracing plate for supporting the 35 flange at the circumference of the head taken on the line 2—2 of Fig. 1, and

Fig. 4 is a cross-sectional view of a modified form of this same bracing plate.

The reel comprises two circular heads 5 of 40 sheet steel and a flanged steel drum 6. Each head has a peripheral outwardly extending flange 7 and a bracing plate 8 made in four sections and fitted to the reel head. The bracing plate 8 is secured in a U-shaped portion 9 formed in the 45 peripheral outward extending flange by bending the end thereof inwardly or it may be secured to this flange by welding, the two structures being shown in Figs. 3 and 4 respectively. The other end of the bracing plate 8 is fastened to the head 50 at a point intermediate its center and circumference by intermittent welds shown at point 10. This type of bracing structure stiffens the head at the periphery as well as gives support to the flange, which is used to support protecting 55 wooden lags 25 which completely enclose the circumferential portion of the reel. The heads 5 are provided with pressed ribs 14 for the purpose of stiffening, and with hand holes 15 to facilitate the assembling of the reel.

60 Hubs 16 placed in holes punched in the centers

of the heads co-operate with a tubular spacer 17 and bolts 18 to hold the center portions of the two heads 5 in fixed relative position. The drum 6 is held against the heads 5 by means of alternate short bolts 19 securing one head to the drum and long bolts 20 passing through both heads and flanges of the drum and so securing the heads to the drum. The reel is shown wound with lead covered telephone cable illustrated by cross-sectioned portion 24, which is protected by wooden lags 25 fitting the flanges 7 and held in place by bands 26 placed in grooves extending circumferentially of the reel, in the manner more fully disclosed in my Patent No. 1,717,834, issued June 18, 1929.

What is claimed is:

1. In a reel for accommodating flexible material, two heads provided with center holes and peripheral outwardly extending flanges, a drum, 80 said drum having inwardly bent flanges, bolts passing through the flanges of the drum and the heads to hold the drum in place, hubs fitting the holes in the center of the heads, a tubular member whose inside diameter is the same as that of the holes fitting the hubs and holding the heads against the hubs, and bolts passing through the hubs and heads for holding the hubs to the heads.

2. In a reel for accommodating flexible material, two heads, a drum having flanges, means for keeping the centers of the heads in uniform 90 relative position, means for holding the drum in position consisting of bolts passing between the heads and through the flanges of the drum, and bolts fastening one flange of the drum to one head, each of said heads having ribs pressed 95 therein and provided with flanges circumferential thereof for accommodating lags secured thereto by bands for protecting and holding the cable on the reel, and bracing means coacting between said flanges and the heads to support the flange and stiffen the head.

3. In a reel for accommodating flexible material, a drum, heads with hand holes to permit 100 easy assembly with the drum, lags to fit the circumference of the heads, each of the heads having flanges to support the lags, a plate extending between the face of the head and the flange for bracing the flange, and bands for securing the lags to the flanges.

4. A reel comprising spaced heads having center 110 holes, hub members fitting said holes, a tubular spacing member whose inside diameter is the same as that of the holes fitting the hubs and holding the heads against the hubs, and means extending through said heads and said hub members for holding said heads and said spacing member together by compression.

ARTHUR ALFRED BUREAU.
